ELECTRICAL CUT-OUT

William James Davy, East Croydon, England

Application August 15, 1931, Serial No. 557,420
In Great Britain September 5, 1930

10 Claims. (Cl. 200—113)

This invention relates to electrical cut-outs wherein the ordinary fusible element is replaced by a column of mercury of relatively small cross-sectional area contained in a tubular body of insulating material. When the column of mercury is subjected to an abnormal flow of electric current the column is ruptured, probably by vaporization due to thermal action, and a portion of the mercury is expelled from the tube so breaking the electrical circuit through the column.

The object of this invention is to provide improved and simplified constructions of such cut-outs which shall be efficient and reliable in operation and which shall comprise simple and effective means for re-establishing continuity in the mercury column.

An electrical cut-out according to the present invention comprises an insulating tube, preferably of some refractory material, metallic pieces at both ends of the tube to make contact between the ends of a mercury column contained within the tube and the external electrical circuit to be controlled by the cut-out, an expansion chamber to contain any mercury expelled from the tube upon rupture of the mercury column therein and means for returning such expelled mercury back into the tube for re-establishing electrical continuity through the mercury column.

In the accompanying drawing; Figs. 1 to 6 are longitudinal sectional views of various forms of cut-outs constructed in accordance with this invention; Fig. 7 is a transverse section of that cut-out shown in Fig. 1, taken on the line 7—7 of this figure.

Similar parts in these figures are indicated by like reference numerals.

Referring firstly to Figs. 1 and 7, it will be seen that the cut-out illustrated comprises an insulating tube 1, of glass or ceramic material for example, sealed at its lower end into a metallic cup 2 which is formed with a small chamber or space 3, adapted to receive mercury, in communication with the bore 4 of the tube, which in practice is also filled with mercury. This bore is shown in Fig. 1 as being slightly enlarged towards each end, the central portion of the bore being of uniform diameter.

At the upper end of the tube 1 is provided a second metallic cup 5 into which the tube is sealed in an air-tight manner but in this case the cup has a straight open passage 6 of larger diameter than, and preferably concentric with, the bore of the tube and forming an overflow or expansion chamber for the reception of mercury extended from the bore of the tube. In order to

prevent the extruded mercury from returning to the bore of the tube 1 by gravity, if the cut-out is to stand in a vertical position, the lower end of the cup 5 is formed with an upwardly coned base 7, the outlet passage 8 from the bore of the tube passing through the apex of this cone.

Suitable contact pins, plugs or the like, such as shown at 9, are secured in the cups 2 and 5 to project laterally therefrom and serve for connecting the cut-out into an external electric circuit.

In order to return the extruded mercury from the overflow chamber 6 to the bore 4 there is provided a manually operated piston or plunger 10 in the overflow chamber with a conical recess 11 to fit exactly over the upwardly coned base 7 of the chamber so that, when the piston is pressed fully inwards, the void in the overflow chamber is completely filled and the extruded mercury is therefore forced back into the tube.

Unless the piston 10 were to fit the chamber 6 with greater accuracy than is possible under conditions of commercial output a certain amount of mercury will force its way between piston and chamber wall when under pressure. An annular groove 12 is therefore formed in the chamber wall at a short distance above the apex outlet 8 of the cone 7, which groove is covered by the piston in its downward movement, to act as a mercury trap from which mercury is returned to the overflow chamber by the first upward movement of the piston.

The plunger or piston 10 may be made of a suitable metal or of a non-metallic substance which is electrically non-conductive, such for example, as the non-conducting materials constituting phenol condensation products and has an extension or stem 13 which projects through an opening in a removable cap or plug 14 of the enclosing insulating body 15 which is cast around the operative parts of the cut-out.

The capacity of the expansion chamber 6 and the permitted amount of upward movement of the piston 10 in the chamber as well as the cross-sectional area of the annular groove 12 forming the mercury trap must be carefully calculated for the varying currents used.

In the construction of cut-outs for the larger currents the upper part of the bore of the overflow chamber 6 is flared, as at 16, in order to catch any surplus mercury which may get above the piston and return it to the lower part of the chamber when the piston is raised. Between the flared top 16 of the chamber and the inner end of the removable closure cap 14 is a space 17,

forming an extension of the overflow chamber 6, into which projects a concentric sleeve 18 fixed in the cap 12. This sleeve is arranged to deflect any mercury which may rise above the flared 5 end 16 of the chamber 6 and return it to the latter.

It will be seen from Fig. 7 that the moulded casing 15 is formed with heat radiating ribs 18 and with a suitable hand-grip 23.

10 The bore 4 of the tube 1 and the chamber 3 in the lower cup 2 may readily be filled with mercury by placing a sufficient quantity thereof in the chamber 6 of the upper cup 5, beneath the piston 10, and alternately raising and depressing 15 the piston or plunger 18, it being found that all the air trapped in these spaces is rapidly displaced by these operations as considerable pressure can be exerted on the mercury.

It may be preferred, however, for purposes of 20 manufacture to connect the upper chamber 6 to a suitable vacuum pump through a two-way cock, which in the one position opens the chamber to communication with the pump and in the other position opens the chamber to communication 25 with a store of mercury. As will be understood, the pump is first allowed to exhaust the air from the interior of the cut-out and the mercury is then allowed to flow in to fill the evacuated space, by suitable manipulations of the two-way cock above-mentioned.

The cut-out, when ready for use, contains mercury in the chamber 3, bore 4 and up to the level of the top of the passage 3 in the cone 7, a small blob of mercury being left in the annular groove 35 around the latter, if desired, to ensure that the bore 4 will always be completely filled whenever the continuity of the column is re-established by depression of the plunger 10.

The action of the cut-out is as follows:—

40 Upon a rupture of the mercury column taking place, due to overheating by the passage of a current in excess of that for which the cut-out is designed, the adjacent ends of the column are forced apart, the upper portion, in part of it, being 45 expelled from the tube 1 through the passage 8 into the overflow chamber 6. The piston 10 is thereby displaced outwardly so uncovering the annular mercury trap 12 and permitting any mercury contained therein to return to the overflow 50 chamber 6. The electrical connection between the pins or plugs 9 is thus broken and the external circuit in which the cut-out is incorporated is therefore interrupted.

When it is desired to re-set the cut-out, the 55 piston 10 is pressed inwards by hand thus displacing the mercury from the overflow chamber 6 into the bore 4 of the tube and reforming the column.

It will be understood that the metal parts in 60 contact with the mercury will be made of a metal or alloy which does not amalgamate with mercury, such, for example, as the alloy of aluminum and manganese which is known as duralumin.

A modified construction of the cut-out shown in 65 Fig. 2 differs only from that shown in Fig. 1 in that the tube 1 is shorter and has a uniform bore 4 and in that the lower cup 2 supports by its upper edge a metal member 2a having a downwardly projecting central nipple 2b the bore 2c 70 of which is in communication with the bore 4 of the tube 1. The other parts corresponding to those of Fig. 1 are similarly designated.

The operation of this form of cut-out is almost 75 identical with that of the form shown in Fig. 1, but in this case a slight amount of air is allowed

to remain trapped above the mercury in the cup 2, around the nipple 2b which extends downwardly into the mercury to provide good electrical connection therewith. Upon rupture of the mercury column the lower portion of the latter is forced 5 downwardly slightly due to the compressibility of the air in the chamber 2, whereby a quick break is ensured, and upon the release of the pressure which occasions such depression of the lower portion of the column, i. e. when the upper portion of the column has been forced out of the bore 4, the compressed air again forces the lower portion of the column part-way up the bore 4. This facilitates the quick re-setting of the cut-out. 15

In Figs. 3 and 4 are shown cut-outs having the piston or plunger disposed laterally of the expansion or overflow chamber proper.

Referring to Fig. 3, the general arrangement, comprising the lower cup 2, tube 1 and upper cup 20 5, is similar to that of Figs. 1 and 2 but the upper cup 5 is modified by being closed at its upper end 5a and by having the conical base 7 with the central aperture 3 formed as a separate part.

In this case any mercury which is extruded 25 into the upper or overflow chamber 6 is allowed to flow out therefrom through a lateral downwardly inclined passage 21 communicating with an additional chamber 22 in which is accommodated a plunger 23 of insulating material. The 30 inner end of the passage 21 opens into an annular groove 21a formed in the wall of the chamber 6 around the lower end of the cone 7.

The additional chamber 22 is formed in the insulating material 15, when this is being moulded 35 around the cut-out parts, by making use of a suitably shaped core and communicates at its lower end through a tapering passage 24 with a bore 25 extending axially through a nipple 26 screwed into the wall of the lower cup 2 so that the bore 40 25 opens into the mercury chamber 3 in the said cup.

A correspondingly shaped tapered extension 21 on the lower end of the plunger 23 is adapted to fill said passage 24 when the plunger 23 is pressed 45 inwardly to the full extent, in which position an annular groove 28 in the plunger registers with the outlet from the passage 21 leading from the chamber 6.

As before, the upper end of the piston or plunger 50 chamber 22 is closed by a plug 14 through which passes the stem 13 of the plunger and in which is secured a central mercury deflecting sleeve 18, the upper portion of the chamber 22 being outwardly flared, as at 22a.

In operation the plunger 23 is fully depressed and the bore 4 of the tube 1 is completely filled with mercury. When a rupture of the mercury column occurs the upper portion is forced out of the bore 4 and through the aperture 8 into the chamber 6, from which it flows through the passage 21 into the groove 28 in the plunger. At the same time the lower portion of the column is depressed and acts to raise the plunger 23 in the chamber 22. 65

When it is desired to re-set the cut-out the plunger 23 is raised sufficiently to allow the mercury in the groove 28 to flow back into the chamber 22, unless the plunger has already been displaced to this extent during the circuit-breaking 70 operation, whereupon the plunger is forced downwardly to press the mercury from the chamber 22, through the passages 24, 25 and chamber 3, back into the bore of the tube 1.

Fig. 4 illustrates a modification of the construc- 75

tion just described, suited more especially for high-amperage cut-outs, in which the upper and lower metallic cups 2 and 5 and the tube 1 with the bore 4 are arranged substantially in the manner shown in and described with reference to Fig. 3.

In this construction, however, the cone outlet from the tube is replaced by an annular member 7a having a central passage 8a, somewhat V-en-turi-shaped, providing communication between the comparatively wide bore 4 of the tube 1 and the expansion or overflow chamber 6. Furthermore, the lateral discharge passage from this chamber is here formed as a tube 29 of insulating material leading into the additional chamber 22 just above the top of the plunger or piston 23 therein, when this plunger is in the fully depressed position.

The upper end of the chamber 22 is flared outwardly at 22a and closed by the plug or cover 14 having secured therein the deflector sleeve 18 and formed with an aperture for the passage of the stem 13 of the plunger 23. The lower end of the chamber 22, however, is formed with an upwardly coned base 30 at the apex of which opens a narrow passage 31 formed in the insulating body 15 and communicating at its lower end with a second narrow passage 32, at right-angles thereto, formed partly in the body 15 and partly in the wall of the cup 2, into the internal chamber 3 of which latter the passage opens.

As described in connection with the plunger 10 of Fig. 1, the lower end of the plunger 23 made entirely of insulating material is recessed conically at 33 in order to fit over the base 30 of the chamber 22.

The operation of the construction just described will be readily understood without further description.

Referring now to Fig. 5, it will be seen that here the general construction of the cut-out is comparable to that of Fig. 1, the sole essential difference being the replacement of the plunger 10 of Fig. 1 by a flexible diaphragm 34.

A modification which follows from this is the omission of the cylindrical expansion chamber 6 of Fig. 1 and its replacement by an expansion chamber 6a the base of which is formed by a dished metal diaphragm 35 having a central up-standing conical nipple 36 and which is secured to the upper cup 5 by the threaded lower end of said nipple.

An axial aperture 37 formed in the nipple 36 extends as the continuation passage 37a in the cup 5 to the top of the bore 4 in the tube 1.

The flexible diaphragm 34 is pressed upwardly at its centre to form a conical depression 38 adapted to fit over the nipple 36 and is secured to a push-button 39 of insulating material which extends through an aperture in the cap or plug 14 which is screwed into the insulating body 15 of the cut-out to hold the diaphragm 34 securely in place.

In operation, the mercury expelled from the bore 4 of the tube 1, upon rupture of the mercury column, is ejected through the passage 37a, 37 into the expansion chamber 6a where it collects around the nipple 36.

To re-set the cut-out, the push-button 39 is depressed to cause the flexible diaphragm to force the mercury in the chamber 6a back into the bore 4 of the tube 1.

Fig. 6 illustrates yet another modification which is strictly equivalent to the form shown in Fig. 1

but differs therefrom in the form of the plunger employed.

The stem 13 of the plunger is secured in an upper nipple 40 on a hollow spherical rubber body 41 having a lower nipple 42 forming the plunger proper and moulded with a recess 41 to fit over the cone 7 in the base of the upper cup 5.

The plunger 42 and the spherical body 41 fit closely against the walls of the expansion chamber 6, an annular mercury trap 43 being formed at the junction of the nipple or plunger 42 with the body 41.

In operation, the mercury expelled from the bore 4 of the tube 1 displaces the plunger upwardly and collects around the cone 7. Upon 15 depressing the plunger by means of the stem 13, in order to re-set the cut-out, the spherical body 41 is flattened somewhat so that its outer wall is forced into close contact with the wall of the chamber 6 and prevents any leakage of mercury 20 upwardly past the trap 43. The mercury collected around the cone 7 is therefore returned into the bore 4 of the tube 1 to re-establish electrical continuity between the cups 2 and 5 and therefore between the plugs 9 secured therein. 25

It will be noted that in all the forms described the cut-out is rendered as air-tight as is possible in practice so that there is no likelihood of loss of mercury. Attention is particularly called to the fact that in this structure, the mercury is designed to be used over and over again, that is, the initial charge of mercury is used repeatedly, this being possible on account of the fact that it is always returned to the bore from the expansion chamber into which it is thrown on rupture of the circuit due to excessive current. Due to the fact that the cut-out is made as air-tight as possible, there is no loss or oxidation of the mercury and consequently it has been found possible to use a given volume thereof indefinitely. 40

It will also be seen that I have provided means for positively forcing back into the tube mercury which has been expelled therefrom and that I have provided means for preventing the return of said mercury to the tube until said manually operable means is positively operated. 45

I claim:—

1. An electrical cut-out of the class described including an insulating tube of narrow bore, a mercury column filling said bore, a metallic piece 50 at each end of the tube and in electrical contact with the corresponding end of the mercury column, a metallic contact member engaged with each contact piece and serving to connect the mercury column in an electrical circuit to be controlled 55 by the cut-out, a chamber in free communication with one end of the bore of the tube and into which mercury is expelled from the tube when the mercury column is ruptured due to the current in the electrical circuit exceeding a predetermined maximum value, and a plunger reciprocatable 60 within said chamber, said plunger and said chamber being formed to provide an annular mercury receiving sealing recess between the surface of the plunger and the surface of the chamber confronting said plunger. 65

2. An electrical cut-out of the class described comprising an insulating tube of narrow bore, a mercury column filling said bore, a metallic piece 70 at each end of the tube, in electrical contact with the corresponding end of the mercury column, a metallic contact member engaged with each metallic piece and serving to connect the mercury column in an electrical circuit to be controlled by the cut-out, a chamber in free communication 75

with one end of the bore of the tube and into which mercury is expelled from the tube when the mercury column is ruptured due to the current in the electrical circuit exceeding a predetermined maximum value, an extension of said chamber arranged laterally of said insulating tube and communicating with that end of said tube remote from the main expansion chamber, and a plunger reciprocatable within said extension, the wall of said extension and the plunger having one an annular sealing recess and the other extending over said recess and closing it when the plunger is depressed.

3. An electrical cut-out of the character described including an insulating tube of narrow bore, a mercury column filling said bore, a metallic member at each end of the tube in electrical engagement with the corresponding end of the mercury column, means whereby the metallic members may be connected in an electrical circuit to be controlled by said cut-out, an expansion chamber in free communication with one end of the bore and having a part thereof extending laterally and below the discharge opening of the bore and into which the mercury is discharged when the mercury column is ruptured due to the current in the electrical circuit exceeding a predetermined maximum value, and means independent of the action of gravity and operative while the cut-out is maintained in its normal position for positively forcing mercury back into the tube.

4. An electrical cut-out of the character described including an insulating tube of narrow bore, a mercury column filling said bore, a metallic element at each end of the tube in electrical engagement with each end of the mercury column, means whereby the metallic elements may be connected in an electrical circuit to be controlled by said cut-out, an expansion chamber having free communication with one end of said bore, means independent of the action of gravity and operative while the cut-out is maintained in normal position for positively forcing mercury discharged into said expansion chamber by rupture back into the tube, means positively preventing the return of mercury back into the tube until said forcing means is operated, a plunger reciprocatable within said chamber, and means for causing mercury forced upward around the plunger to form a seal across the joint between the plunger and the contacting wall of the chamber.

5. An electrical cut-out as in claim 4 having means for permitting the mercury forming the seal to descend below the plunger when the plunger is raised.

6. An electrical cut-cut of the class described, comprising an insulating tube of narrow bore, a mercury column filling said bore, a metallic piece at each end of the tube in electrical contact with the corresponding end of the mercury column, means whereby the metallic pieces may be connected in an electrical circuit to be controlled by said cut-out, an expansion chamber in free communication with one end of the bore of the tube and into which mercury is expelled from the tube when the mercury column is ruptured, an extension chamber arranged laterally of said insulating tube, there being a downwardly extending duct extending from the lower portion of said expansion chamber downward and opening into said extension chamber, the lower end of the extension chamber having an upwardly tapered nipple, the nipple having a bore communicating

with that end of said tube remote from the expansion chamber, the upper end of said extension chamber being enlarged, and a plunger located in said extension chamber and having a recess in its face confronting the nipple and fitting the nipple, the plunger being of a length less than the distance between the extreme lower end of the extension chamber and said duct whereby mercury forced up around the piston when the piston is depressed will collect above the piston and seal the joint between the piston and the wall of said extension chamber, the enlarged upper end of the extension chamber permitting the mercury to flow back into the lower end of the extension chamber when the plunger is fully raised.

7. An electrical cut-out of the class described including an insulating tube of narrow bore, a mercury column filling said bore, a metallic member at each end of the bore in electrical contact with the corresponding end of the mercury column, means for connecting the metallic members in an electrical circuit to be controlled by the cut-out, an expansion chamber in free communication with one end of the bore of the tube and into which mercury is expelled from the tube when the mercury column is ruptured, a plunger disposed in said chamber and adapted when depressed to positively force mercury discharged into said chamber back into the tube, and a diaphragm extending between said plunger and the wall of the expansion chamber, and constituting a seal.

8. An electrical cut-out of the class described, including an insulating tube of narrow bore, a mercury column filling said bore, a metallic piece at each end of the tube in electrical contact with the corresponding end of the mercury column, a metallic contact member engaged with each metallic piece and serving to connect the mercury column in an electrical circuit to be controlled by the cut-out, a chamber in free communication with one end of the bore of the tube and into which mercury is expelled from the tube when the mercury column is ruptured due to the current in the electrical circuit exceeding a predetermined maximum value, piston means independent of the action of gravity and operative while the cut-out is maintained in its normal position for positively forcing mercury discharged into said chamber by rupture back into the tube, means for positively preventing the return of mercury to the tube until said piston means is operated and means affording a seal around the periphery of the piston when the piston is depressed.

9. An electrical cut-out of the class described, including an insulating tube of narrow bore, a mercury column filling said bore, a metallic piece at each end of the tube in electrical contact with the corresponding end of the mercury column, a metallic contact member engaged with each metallic piece and serving to connect the mercury column in an electrical circuit to be controlled by the cut-out, a chamber in free communication with one end of the bore of the tube and into which mercury is expelled from the tube when the mercury column is ruptured due to the current in the electrical circuit exceeding a predetermined maximum value, piston means independent of the action of gravity and operative while the cut-out is maintained in its normal position for positively forcing mercury discharged into said chamber by rupture back into the tube, means for positively preventing the return of

mercury to the tube until said piston means is operated, and means securing a mercury seal between the piston and the wall of the chamber when the piston is depressed.

- 5 10. An electrical cut-out of the class described, including an insulating tube of narrow bore, a mercury column filling said bore, a metallic piece at each end of the tube in electrical contact with the corresponding end of the mercury column, a 10 metallic contact member engaged with each metallic piece and serving to connect the mercury column in an electrical circuit to be controlled by the cut-out, a chamber in free communication with one end of the bore of the tube and into which mercury is expelled from the tube when the mercury column is ruptured due to the current in the electrical circuit exceeding a predetermined maximum value, piston means independent of the action of gravity and operative while the cut-out is maintained in its normal position for positively forcing mercury discharged into said chamber by rupture back into the tube, means for positively preventing the return of mercury to the tube until said piston means is 10 operated and means for trapping mercury around the piston when the piston is depressed.

WILLIAM JAMES DAVY.
